UNITED STATES PATENT OFFICE.

HAROLD A. BIERCK, OF PHILADELPHIA, PENNSYLVANIA.

METHOD OF OPERATING MUSICAL INSTRUMENTS FROM A SINGLE SOURCE OF POWER.

1,247,363.

Specification of Letters Patent.

Patented Nov. 20, 1917.

Original application filed January 22, 1914, Serial No. 813,663. Divided and this application filed July 6, 1914. Serial No. 849,230.

To all whom it may concern:

Be it known that I, HAROLD A. BIERCK, a citizen of the United States, residing in the city and county of Philadelphia, State 5 of Pennsylvania, have invented a new and useful Method of Operating Musical Instruments from a Single Source of Power, of which the following is a specification.

This application is a division of an application for Letters Patent for improvement in combination blower, Serial No. 813,663, filed by me on the 22nd day of January, 1914.

In moving picture theaters, it has recently become the practice to install what is commonly termed a moving picture orchestra, the same comprising three distinct elements,—the organ element, which must be operated by suitable pressure creating or blowing devices, and the piano element, and the mechanicals, that is, mechanical instruments, such as snare drums, base drums and the like, said piano and mechanicals being heretofore operated by a separate suction 25 creating device.

It has heretofore been the practice to employ a motor coupled to a blower or a pressure creating device for blowing or operating the organ, and a second motor 30 connected with suction creating or vacuum devices for operating the piano and the mechanicals. This has, consequently, necessitated the employment of two distinct electric motors and two distinct sets of mechanism for creating the suction or vacuum and the pressure for the above-described elements, which has consequently entailed the expense of supplying electricity to two electric motors, and there has, in addition, 35 been a great deal of space taken up by the pressure and suction or vacuum devices, respectively, and, in some instances, provision has had to be made for a special or additional room for either or both of said 40 suction or vacuum and pressure devices.

It has also heretofore been the practice in producing the vacuum or suction, to have an electric motor coupled to a device converting rotary motion into reciprocating 45 motion and communicating such motion to a bellows or similar device, whereby the required suction was produced. As these

machines generally run continuously for a period of ten to twelve or fourteen hours a day, the leather of which the bellows or 55 suction devices were constructed would become liable to crack and open, thus allowing the suction to be broken, and cause a cessation of operation of the musical instruments actuated thereby. In the case of the 60 pressure creating apparatus, it was also necessary to have a separate motor and a separate pressure creating apparatus, which was ordinarily considerably larger in size, and generally had to have a special compartment, 65 wherein the same could be placed. Furthermore, the ordinary speed of an organ blower is generally 1165 revolutions per minute; consequently, the organ blower would necessarily have to be made so large 70 that it would be impractical, if not impossible, to place it in the average moving picture theater, and, in addition to the blower being very costly to build, it required a motor of considerable horse power. 75

By my present invention, I locate the suction or vacuum and pressure creating apparatus upon a single main shaft, which is inclosed in a box or casing of novel construction, so as to be rendered practically 80 sound-proof, said casing being provided with a pressure outlet, leading from said casing to the organ, which is in co-operative communication with the pressure creating devices, and I also provide the casing with 85 an inlet or suction connection, whereby suction is created for the piano and the mechanicals, whereby the organ, piano and mechanicals are properly operated at the desired periods. 90

By my invention, it is only necessary to employ a single motor, coupled to a single main shaft, upon which a pressure fan and a plurality of suction fans are mounted, it being necessary to employ a greater number 95 of suction fans than pressure fans, because three duties are required or three operations performed, by the suction end of the apparatus.

- a.—Turning the piano roll;
- 100 b.—Operating the pneumatics; and
- c.—Operating the mechanicals.

By my present invention, space is economized, and the expense for electricity is

greatly reduced from what it has been heretofore, because I only employ a single motor and a single main shaft, and since all the operative elements are mounted thereon, there is a constant suction or vacuum and a constant pressure, dependent upon the speed of rotation of the motor. In addition, the construction of the moving picture orchestra is greatly simplified, since the builder is enabled to utilize the room which was heretofore taken up by the former suction devices.

It will also be apparent that the matter of the electric motor wiring is much simplified as it is reduced one-half by the employment of a single motor, since it was heretofore necessary to connect up two circuits for two independent motors, whereas in my present invention, only a single motor is employed, and there is, of course, but a single motor to get out of order, as compared with the two motors heretofore employed. Furthermore, by my present invention, where a combination blower is employed, the same can be placed in a separate room or in some location away from the moving picture orchestra, which is a great improvement over prior constructions, as heretofore it has been generally considered necessary to have the motor inside the piano or inside the moving picture orchestra, which was dangerous on account of fire, as the motor was necessarily inclosed in the orchestra casing.

My invention consists in a novel method of operating an organ, a piano and the mechanicals of a moving picture apparatus from one common source of suction and air pressure production, actuated by one individual motor.

For the purpose of illustrating my invention, I have shown in the accompanying drawings, one form thereof which is at present preferred by me, since it will be found in practice to give satisfactory and reliable results, although it is to be understood that the various instrumentalities of which my invention consists can be variously arranged and organized, and that my invention is not limited to the precise arrangement and organization of these instrumentalities as herein shown and described.

Figure 1 represents a longitudinal, sectional view of a combination blower embodying my invention, certain of the parts being shown in elevation.

Fig. 2 represents a section on line $x-x$, Fig. 1.

Fig. 3 represents a section on line $y-y$, Fig. 1.

Fig. 4 represents a perspective view of the box in which the principal operative parts are contained, the same being shown in detached position.

Fig. 5 represents a sectional view of the pressure creating apparatus.

Fig. 6 represents a sectional view of one element of the vacuum or suction creating apparatus.

Fig. 7 represents a diagrammatic view, showing the manner of connecting up my invention to the organ, the piano and the mechanicals.

Similar numerals of reference indicate corresponding parts in the figures.

Referring to the drawings:—

1 designates the motor, which may be of any suitable type, and is mounted upon a plate 2, through which pass the leveling screws 3, which are supported upon the frame or body 4, and provided with a series of nuts 5, 6 and 7, by the proper manipulation of which, the motor can be raised or lowered, so that its shaft 8 may properly align with the main shaft 9 of the combination suction and pressure creating apparatus. The shafts 8 and 9 are connected by means of a suitable coupling 10, and as these parts *per se* form no part of my present invention, a detailed description thereof will be unnecessary.

11 designates a plurality of standards or bearings supported on the frame 4, in which the main shaft 9 rotates, preferably upon suitable ball bearings, said main shaft having secured thereto the vacuum or suction fans 12, 13, 14, 15 and 16, which in the present instance are five in number, and are separated from each other by the partitions 17, the partition 18 separating the fan 12 from the end 19 of the inclosing box 20.

All of the suction fans 12 to 16 are constructed substantially alike, as will be understood from Fig. 6, and each comprises the hub 21 and the upright disk or body portion 22, having the curved blades 23, against which the disk or plate 24 is secured, the latter having the opening 25 for the suction or ingress of the air which enters the port 26, through the suction pipe 27. 28 designates an upper series of blocks, which latter are secured to the upper portions of the partitions 17, as seen in Fig. 1, said blocks having secured thereto the plates 29, the extent and contour of which will be understood from Figs. 1 and 3, similar blocks and plates 30 and 31, respectively, being located in the lower portions of the box 20, as will be understood from Figs. 1 and 3. The hubs 21 of the suction fans 12 are secured to the main shaft 9 by any suitable means, and it will be apparent that as said shaft is rotated in the proper direction, the suction will be created through the vacuum or suction inlet 27, port 28, the suction fan inlet 25, and the air will pass out the outer periphery of the suction fan 12 and thence around the respective partitions and plates direct through the other suction fans to the outlet port 32, passage 33 and outlet port 34 in the manner familiar to those skilled in this art. The

partitions 35 divide the series of suction fans from the pressure fan 36, which is contained in the pressure chamber 37, which is formed by the partitions 35 and 38, to the left of which latter is located the inlet chamber 39, into which air is drawn from the atmosphere through the ports 40. The construction and location of the pressure fan will be understood from Figs. 1, 2 and 5, 10 said pressure fan having the hub 41, the plate or disk 42, upon which are cast or otherwise secured the curved blades 43, (see Figs. 2 and 5), to which is secured the plate or disk 44, having the inlet opening 45 into 15 which air is drawn through the opening 46, which communicates with the inlet passage 39, the air which is drawn in through the ports 40 being forced through the outlet port 47 into the pressure or outlet nozzle 48 to the 20 desired point, as will be hereinafter explained. The suction fans 12, 13, 14, 15 and 16 are substantially alike, and are similar to the pressure fan 36, except that I preferably make the latter somewhat larger or 25 of greater power, it being noted that the pressure fan 36 has its inlet at the left, as will be understood from the left-hand portion of Figs. 1 and 5, while the suction fans have their inlets at the right, as will be 30 understood from the right-hand portion of Figs. 1 and 6, the conjoint operation of the suction fans being apparent to those skilled in the art, it being noted that the suction fans and the pressure fan are mounted upon 35 the same main shaft so that but a single motor is required to operate them.

In carrying out the broad embodiment of my invention, which comprises the conjoint creation of a vacuum and a pressure within 40 a single casing by combined apparatus mounted upon a common main shaft and actuated by a single motor, whereby a combined or conjoint operation is produced through the medium of the motor and single 45 shaft common to the suction and pressure devices, it will be apparent that any desired form of inclosing casing may be employed, so long as the requisite suction and outlet ports and inlet and pressure discharge ports 50 are located in the proper positions with respect to the vacuum and pressure creating devices, respectively.

I have, however, in the present instance, 55 designed a form of inclosing casing, which I preferably employ, the construction of which may be varied in accordance with requirements. The hereinbefore described suction and pressure creating devices are located in a sectional box 20, best seen in 60 perspective in Fig. 4, said box being composed of the upper and lower sections 49 and 50, respectively, which are superimposed upon each other and held in assembled position by means of the side strips 51 and 65 end strips 52, which latter are secured to the

box members, which may be of wood or similar material, in any suitable manner. Around the box 20, I place a layer of felt or similar material 53, which surrounds the sides, ends and top of the box, and around 70 this felt, I place a metallic casing 54, and secure the same to the frame or bed 4 by means of the straps 55. I also secure to the ends 19 of the box, angle irons 56, whose feet 57 are secured to the frame 4 by any 75 suitable fastening devices, as the bolts 58, the location of said angle irons being understood from Fig. 1.

I also secure the ends 19 of the box and their adjuncts in position by means of the 80 long screws 59, as will be seen in Figs. 1 and 3, whereby an exceedingly rigid, efficient and sound-proof structure is produced, wherein vibration is reduced to a minimum, and which is exceedingly durable. The 85 frame 4 is supported upon the bed of felt or similar material 60, best seen in Figs. 1 and 3, the latter being supported upon the base 61, which may be of wood or similar material. 90

By the employment of the above-described construction, I have found that an exceedingly durable and efficient construction is produced, wherein the objectionable humming or vibration heretofore existing in 95 blowing devices has been reduced to a minimum.

While the broad embodiment of my invention comprises the operation of the conjoint vacuum and pressure creating apparatus 100 upon a single common main shaft and within a single casing, in the practical application of my device, I connect the pressure outlet 48 by means of the pipe 67, with the blowing apparatus or pressure inlet apparatus of the 105 organ 62, seen in Fig. 7, and I also connect the suction inlet 27, seen in Figs. 1 and 7, with the suction pipe 63, which leads from a box 64, having a branch 65, which leads to the piano 68, and a branch 66, which leads 110 to the operating mechanism for the mechanics 69.

I deem it unnecessary to enter into any 115 detailed construction of the organ member or the piano or mechanicals shown diagrammatically in Fig. 7, since the same form, *per se*, no part of the present invention.

I also deem it unnecessary to describe the 120 operation of these devices further than to show that the pressure pipe 67, conducts the pressure to the organ 62, or, in other words, blows the latter, while by the suction pipe 63, I am enabled to create the necessary suction or vacuum to operate the piano element 68 and the mechanicals 69 in the customary 125 manner, it being apparent that I am enabled by my novel construction, to attain the desired actuation of the organ, piano and the mechanicals, through the medium of my novel pressure and suction devices, which 130

are contained in a single casing and operated from a common shaft, by a single motor, wherein the expense heretofore incident to the operation of these devices is reduced 5 or diminished.

It will be apparent that the rotation of the motor will operate the main shaft 9 and give to the suction fans 12, 13, 14, 15 and 16 and pressure fan 36, a steady and constant rotation, and the requisite vacuum and pressure will be created at the desired points 10 and for the desired purposes.

It will be understood that the partitions 18, 17, 35 and 38 are preferably of wood or 15 similar material, and are in substantial alignment above and below the main shaft 9, said partitions being secured to the box 20 in any suitable manner, and extending across said box, having an opening in the middle of 20 sufficient size for the main shaft 9 and hubs 21 to pass through. The upper and lower blocks 28 and 30 are also preferably of wood, and secured to the contiguous partitions 17, as will be understood from Fig. 1, 25 while the plates 29 and 31, which are secured to the blocks 28 and 30, are preferably of metal.

I have deemed it unnecessary to describe

or show in detail the specific manner of securing the partitions to the blocks and plates 30 in assembled position, as this will be apparent to those skilled in the art, and may be varied according to requirements.

Other modes of applying the principle of my invention may be employed for the mode herein explained. Change may therefore be made as regards the mechanism thus disclosed, provided the principles of construction set forth, respectively, in the following claim are employed.

Having thus described my invention, what I claim as new and desire to secure by Letters Patent, is:—

The herein described method of actuating a plurality of musical instruments, some by 45 vacuum and others by pressure, which consists in simultaneously creating a vacuum and a pressure for operating the instruments and synchronously varying the vacuum and pressure always in the same proportion, whereby the sound from the instruments are kept in harmony.

HAROLD A. BIERCK.
